UNITED STATES PATENT OFFICE.

ERNEST C. GOETTING, OF NEW YORK, N. Y.

DESIGN FOR A SHOW CARD OR STAND.

SPECIFICATION forming part of Design No. 20,124, dated September 2, 1890.

Application filed July 22, 1890. Serial No. 359,567. Term of patent 3½ years.

To all whom it may concern:

Be it known that I, ERNEST C. GOETTING, of the city, county, and State of New York, have invented and produced a new and original Design for Show Cards or Stands, of which the following is a specification.

Reference is to be had to the accompanying drawing, forming a part of this specification, in which the figure is a perspective view of the design.

The leading feature of the design consists in the figure or representation of a wall or paper basket A, on the surface of which appears a series of bottle-like figures B, apparently supported on the said wall or paper basket A. The wall or paper basket A appears with an ordinary rectangular back figure C, from which appears to project a like

rectangular figure D, somewhat less in size than the back figure C. Both the back figure C and the figure D appear with bottle-like figures, as is plainly shown in the design. An arm or rod E appears to project from the back figure C of the wall-basket.

I claim—

The design for a show card or stand herein shown and described, the same comprising the representation of a wall or paper basket and a series of bottle-like figures appearing to be supported on the said wall or paper basket.

ERNEST C. GOETTING.
